(57) **CLAIM**

The ornamental design for a connector, as shown and described.

DESCRIPTION

1. Connector

1.1 : Perspective

1.2 : Front

1.3 : Back

1.4 : Left

1.5 : Right

1.6 : Top

1.7 : Bottom

The present design is a connector for an optical cable; the broken line portions are shown to illustrate environment only and form no part of the claimed design.
